UNITED STATES PATENT OFFICE.

EDWARD A. ESCHINGER, OF PHILADELPHIA, PENNSYLVANIA, ASSIGNOR
TO LANSTON MONOTYPE MACHINE COMPANY, OF PHILADELPHIA, PENN-
SYLVANIA, A CORPORATION OF VIRGINIA.

TYPE-MOLD.

No. 857,728.

Specification of Letters Patent.

Patented June 25, 1907.

Application filed December 10, 1904. Serial No. 236,347.

To all whom it may concern:

Be it known that I, EDWARD A. ESCHINGER, a citizen of the United States, residing at Philadelphia, in the county of Philadelphia and State of Pennsylvania, have invented 5 certain new and useful Improvements in Type-Molds; and I do hereby declare the following to be a full, clear, and exact description of the same, reference being had to the accompanying drawings, forming a part of this specification, and to the figures and letters of reference marked thereon.

This invention relates more especially to the class of type casting machines wherein 15 the mold is provided with a divided or sectional mold-blade and means for actuating or adjusting said sections separately, or together, for the production of full-body type or low quads or spaces, after the manner disclosed in application Serial No. 135,632, of Dec. 17, 1902, and it has for its principal objects to prevent the springing or displacement of the outer or upper mold-blade section, and to simplify and improve the control devices or mechanism through which the sections are connected for simultaneous action, or disconnected for dissimultaneous adjustment; to which ends the invention consists in the construction, combinations and 25 arrangements of parts hereinafter fully described, the novel features whereof are set forth in the appended claims.

In the accompanying drawings illustrating a preferred form of embodiment—Figure 1 is 30 a top plan view of the improved mold with the mold-blade actuating and adjusting devices applied thereto. Figs. 2, 3 and 4, are sectional views parallel with and to one side of the mold-blade showing the latter in different positions of adjustment. Fig. 5 is a perspective view showing the mold-blade sections and latch detached.

Corresponding numerals designate like parts in the several figures.

45 The improvements are shown applied to the mold of Patent No. 752,814, whereof 1 is the cross-block, 2 the side-blocks, 3 the type block squaring plate, 4 the base section, 5 the gage block and holding down guide for 50 the mold-blade, 6 the mold-blade front stop or gage, 7 the cross-pin connecting the mold-blade with its actuating and adjusting mech-

anism and 20 the matrix. The integral mold-blade of the patent is replaced by one divided longitudinally into sections 8, 9, whereof 55 the lower or body section 8 corresponds generally, except as to its vertical dimensions, with the mold-blade of the prior mold, and is provided with an opening for the reception of the gage block and top guide 5, 60 another for the cross-pin 7, and a third for the front stop 6. The upper or cut-off section 9 is in the form of a straight and relatively narrow strip overlying and resting upon the upper edge of the body section 8, 65 and provided with a longitudinal beveled bearing or guiding surface 10, the latter co-operating with an overlapping beveled shoulder on the side block. The bevel 10 extends to a point in close proximity to the casting 70 face of the section, being interrupted at or near the vertical enlargement forming part of the matrix seat at which point the cut-off section is rectangular and of a width corresponding with that of the body section, the 75 side walls of the mold cavity being maintained in parallel relation. By these means a strong and rigid top guide for the cut-off section is provided, one well calculated to resist the impact and pressure of the molten 80 metal in the mold cavity and to maintain a metal tight joint between the two sections, a condition of the utmost importance, and this too without weakening the upper section by cutting away the material or increasing 85 the vertical dimensions of the mold in a manner to interfere with its use in connection with type casting and composing machines of the class illustrated in Patent 625,998. The better to accomplish this result, *i. e.*, 90 prevent the springing or displacement of the upper or cut-off section 9, while at the same time permitting free movement either in conjunction with or independent of the lower or body section 8, the beveled bearing surface 95 10 is preferably formed upon a lateral extension of the upper or cut-off section, thus leaving the body of full vertical and lateral dimensions, with its upper face flush with that of the side blocks and of a width substantially equal to that of the end portion between the side blocks.

To increase its rigidity and facilitate action the rear portion of the cut-off section 9

is provided with a vertical extension or plate 11, off-set to one side of the plane of said section and extending in parallel relation with the rear end of body section 8. This plate 11 takes its lower bearing upon the lower face of the slot in squaring plate 3 along one side of the body section 8, and it, together with the body section, is held down upon said squaring plate and a rear extension thereof 10 by the front stop 6 which is made vertically adjustable for this purpose, so that said front stop, in addition to its normal function as a gage in limiting the extreme forward positions of the two sections, serves as a top 15 guide for the rear of the two sections by its contact with the lower surfaces of the openings, through which it is passed.

It is to be noticed that the opening in the rear end of plate 11 for the passage of cross-pin 7 is longer than that in the body section, to permit the requisite degree of independent movement of the cut-off section.

When the mold is employed for producing full-body or character type the two mold-blade sections should be maintained in fixed relation to each other with their casting faces in the same plane, and when short or low quads and spaces are required, said sections should be uncoupled so as to be capable of 30 independent movement, the one to cut-off or close the matrix end of the mold and the other, to measure the width of the mold cavity below or in rear of the cut-off. A simple and effective means for accomplishing these 35 results has been devised and is illustrated, in a preferred form, in the drawings. It consists, essentially, of a pawl or latch 12 pivotally mounted upon the cut-off section 9 in position to engage a shoulder 13 on the body 40 section 8 when the casting faces of the two sections are in alinement, said latch being coupled with a spring 14 attached to the mold and provided with an operating arm 15 in position to be engaged by a lever 16 or 45 other actuator. As shown applied the latch 12 is pivoted upon the side of plate 11 near the rear upper corner thereof, and its engaging portion extends laterally in the form of a web or flange, over plate 11 and the rear portion of the body section 8, while the arm 15 is curved forward and downward to avoid cross-pin 7. Both the body section 8 and plate 11 are notched, as at 17, to accommodate 50 the overlapping portion of the latch, and the spring 14 is applied in a manner to advance the latch into engagement with shoulder 13 and to apply pressure to the upper or cut-off section 9 in a direction to advance the latter. With the parts thus 55 constructed and arranged, when it is desired to produce full-body or character type the two mold-blade sections stand with their casting faces in alinement and the latch 12 in engagement with shoulder 13, as represented in 60 Fig. 2, so that the movements, for adjust-

ment and ejection, communicated to the cross pin will be transmitted to both sections of the mold-blade. It will be noted that under these conditions spring 14 operates upon latch 12 to hold it against shoulder 13, said latch and shoulder serving as gaging members for determining the relative position of the two sections to which they are respectively attached. So long as the two mold-blade sections remain thus locked together 70 they operate the same as an integral mold blade; and when it is desired to produce a low quad or short-body type, it is only required that pressure should be applied to the latch 12 in a direction to disengage shoulder 80 13, in the present instance corresponding with the pull of spring 14. The latch can be operated upon directly or through the medium of lever 16, but it is preferably controlled automatically and from the record strip, directly or indirectly through selected matrices as illustrated in Patent No. 828,450, dated 85 Aug. 14, 1906. Latch 12 is operated, to disconnect the mold-blade sections during the withdrawal of the cross-pin from the ejecting position, Fig. 4, whereby the upper or cut-off section 9, being no longer controlled by said cross-pin, is advanced or held by its spring 14 in contact with the opposite wall of the mold-cavity, as seen in Fig. 3, leaving the 90 body section subject to the action of the cross-pin. After the cast is made the body section 8 is advanced to eject the type when both sections contact with the front stop, thus bringing their casting faces into alinement, whereupon latch 12 reengages shoulder 13 and the two sections are again locked together in position for either simultaneous or dissimultaneous readjustment in the mold 95 as desired.

It will be observed that in the preferred form of embodiment disclosed herein the mechanism for effecting the simultaneous and dissimultaneous adjustment of the mold-blade sections, with the possible exception of the attachment for spring 14, is self contained, and, moreover, that it is applicable to existing forms of mold by the substitution of one side block (that containing the top bearing for the upper section) or the grooving of the same to accommodate bearing 10 and a slight widening of the slot in block 3 to afford accommodation for the increase in width due to the presence of plate 11.

Having thus described my invention, what I claim as new and desire to secure by Letters Patent, is:—

1. A type mold such as described provided with a longitudinally divided or sectional mold-blade, the upper or cut-off section 125 whereof is furnished with a beveled guiding surface co-operating with an overlapping guide on the side block forming a top guide for said section.

2. A type mold, such as described, pro- 130

vided with a sectional mold-blade, the lower or body section whereof is provided with an internal top guide, and the upper or cut-off section with an overlapping top guide carried by the side block.

3. A type mold, such as described, provided with a sectional mold-blade the upper or cut-off section whereof is provided with a lateral extension or flange projecting beneath a top guiding surface on the side block.

4. A type mold, such as described, provided with a sectional mold-blade, the two members or sections whereof are each provided with two top guides, the one applied near the casting faces and the other to the rear portion.

5. A type mold, such as described, provided with a mold-blade composed of superposed independently movable sections, of which latter the lower or body section is provided with transverse openings for the reception of the gage block and front stop, the latter operating as top guides, while the upper or cut-off section is provided with an opening in its rear portion for the front stop, and a longitudinal side bearing engaged by an overlapping portion of the side block, forming a top bearing therefor.

6. A type mold such as described provided with a mold-blade composed of superposed independently movable sections of which the upper or cut-off section is provided with an off-set vertical extension or plate in parallel relation with the lower or body section.

7. A type mold such as described, provided with a mold-blade composed of superposed independently movable sections, the upper or cut-off section whereof is furnished with a bevel surface extending longitudinally thereof and projecting beneath or bearing on the side block to form a top guide.

8. A type mold such as described provided with a divided mold-blade composed of superposed independently movable sections, the upper or cut-off section whereof is furnished with a top bearing surface in the form of a bevel engaged by an overlapping bearing on the side block, said bevel and bearing terminating near without entering the mold-cavity.

9. A type mold such as described provided with a divided mold-blade composed of superposed longitudinally movable sections, one of said sections carrying a pivoted latch coöperating with a shoulder on the other section.

10. In a type mold such as described, provided with a divided mold-blade, and in combination therewith, a latch pivotally supported upon one section in position to engage a shoulder on the other section when the casting faces are in alinement, adjusting devices coupled with one of said sections and an elastic pressure device coupled with the other section, to advance and hold the latter when the latch is disengaged.

11. In a type mold such as described provided with a divided mold-blade and in combination therewith a one way yielding latch mounted upon one mold-blade section in position to automatically engage a shoulder on the other section when their casting faces are in alinement, and an actuating connection or cross-pin coupled with one section.

12. In a type mold such as described provided with a divided mold-blade and in combination therewith a latch pivotally supported upon the cut-off section in position to engage a shoulder on the body section, when their casting faces are in alinement, a front stop for alining the two sections, and actuating devices coupled with the body section for simultaneous adjustment.

13. In a type mold such as described and in combination with the divided mold-blade thereof, a latch pivoted upon one section in position to engage a shoulder on the other section, a spring coupled with said latch to advance the section on which it is carried, and means for actuating said latch to uncouple the sections for individual adjustment.

14. In a type mold such as described provided with a divided mold-blade and in combination therewith, the latch pivoted upon and carried by the cut-off section in position to engage a shoulder on the body section and provided with an actuating arm; a spring for advancing and holding the cut-off section; adjusting devices coupled with the body section, and a lever in position to engage the actuating arm of the latch.

15. In a type mold such as described provided with a divided mold-blade composed of superposed independently movable body and cut-off sections the latter provided with a vertical extension off-set and lying in parallel relation with the body section; a front stop for both sections; a cross-pin engaging the body section; a pawl pivoted upon the extension of the cut-off section in position to engage a shoulder on the body section; a spring attached to the mold and engaging said pawl; and means for actuating the pawl to disengage it from the shoulder on the body section.

16. A type mold such as described provided with a mold-blade composed of superposed independently movable sections of which one section is provided with an off-set portion in parallel relation with one side of the other section.

17. A type mold such as described provided with a divided mold-blade, the upper or cut-off section whereof carries an off-set portion in parallel relation to the lower or body section and a pivoted latch engaging a shoulder on said body section, the latter being provided with means for attachment to the adjusting devices.

18. A type mold such as described pro-

vided with a sectional mold-blade and top guides applied to the rear portions of each of said sections.

19. A type mold provided with a sectional mold-blade and a front stop or gage, the latter engaging said sections to form a top guide therefor.

20. The combination with a type mold such as described, provided with a sectional mold-blade, a latch carried by one of said sections and interlocking with the other section, of a lever supported in fixed relation to said latch and adapted to contact therewith.

21. In a type casting machine, a matrix, a mold having a slot leading to the face of the matrix, main and auxiliary blades for determining the width of the slot, means for connecting and disconnecting the main and auxiliary blades, and a spring for moving the

auxiliary blade forward to cut off the slot at 20 a distance from the matrix when the blades are disconnected.

22. In a type casting machine, a matrix, a type mold having its slot leading to the face of the matrix, main and auxiliary blades for 25 determining the width of the slot, means for disconnecting the blades a spring for moving the auxiliary blade forward to cut off the slot at a distance from the matrix and means for moving the main blade forward to eject the 30 lead, connect it with the auxiliary blade and move the main and auxiliary blades back to their normal position.

EDWARD A. ESCHINGER.
